[57] CLAIM

The ornamental design for a spray gun for aerosol can, as shown and described.

DESCRIPTION

FIG. 1 is a perspective view of a spray gun for an aerosol can showing my new design;

FIG. 2 is a top plan view thereof;

FIG. 3 is a right side elevational view thereof, the left side being a mirror image of the right side shown;

FIG. 4 is a front elevational view thereof;

FIG. 5 is a rear elevational view thereof; and

FIG. 6 is a bottom plan view thereof.

The broken line representation of an aerosol can in FIG. 1 is for purposes of illustration only.

FIG. 1

FIG. 2

FIG. 3

FIG. 4

FIG. 5

FIG. 6
